UNITED STATES PATENT OFFICE

112,373

DESIGN FOR A BOTTLE

Charles W. Monn, Cedar Rapids, Iowa

Application September 24, 1938, Serial No. 80,078

Term of patent 14 years

To all whom it may concern:

Be it known that I, Charles W. Monn, a citizen of the United States, residing at Cedar Rapids, in the county of Linn and State of Iowa, have invented a new, original, and ornamental Design for a Bottle, of which the following is a specification, reference being had to the accompanying drawing, forming a part thereof.

In the drawing:

Fig. 1 is a front elevational view of a bottle showing my new design.

Fig. 2 is a side elevational view thereof.

Fig. 3 is a top plan view thereof.

I claim:

The ornamental design for a bottle, substantially as shown.

CHARLES W. MONN.
